Attorney

UNITED STATES PATENT OFFICE.

SCOTT A. BROCKWAY, OF FORDYCE, NEBRASKA.

ALLIGATOR-WRENCH.

No. 923,940.

Specification of Letters Patent.

Patented June 8, 1909.

Application filed April 13, 1908. Serial No. 426,846.

To all whom it may concern:

Be it known that I, SCOTT A. BROCKWAY, a citizen of the United States, and a resident of Fordyce, in the county of Cedar and State 5 of Nebraska, have invented certain new and useful Improvements in Alligator-Wrenches, of which the following is a specification.

My invention relates to wrenches of the alligator-jaw type, and has for its object the 10 provision of a wrench in which one jaw and its operating arm are formed integral and rigidly secured in a suitable casing, while the other jaw is pivotally secured in the casing and provided with gear-teeth, and the operating-handle therefor is also pivotally secured in the casing and provided with gear-teeth meshing with the gear-teeth on the pivoted jaw, a spring being provided to hold 15 the pivoted handle so that the jaws are open.

20 The construction and operation of my improved wrench will be described hereinafter and illustrated in the accompanying drawings, in which—

Figure 1 is a side view of my improved 25 wrench; and Fig. 2, a similar view, showing a portion of the casing removed.

In the drawings similar reference characters indicate corresponding parts in both views.

30 1 indicates a casing preferably made in two parts and held together by means of the screws hereinafter particularly described.

2 indicates a fixed jaw having a handle 3 formed integral therewith, said jaw and the 35 handle being secured in the casing 1 by means of screws 4. 5 indicates another jaw pivotally secured in casing 1 by means of screw 6 and having gear-teeth 7 on its rear end.

40 8 indicates a handle pivotally secured in the casing by means of screw 9, and having gear-teeth 10 on the end inside of the casing that mesh with the gear-teeth 7 on the jaw 5.

11 indicates a coil-spring seated on handle 3 and engaging a notch 12 in the under side 45 of handle 8, the purpose of said spring being to throw the handle 8 away from handle 3, which operates through the instrumentality of gear-teeth 7 and 10 to move jaw 5 away from jaw 2, it being understood that the 50 wrench is operated to close the jaws into an operative position by squeezing the handles 3 and 8 together, while by releasing the pressure on said handles the jaws are opened to release them from engagement with the nut 55 or other object.

13 indicates a shield secured to handle 3 to hold spring 11 in place when the jaws are open and which engages socket 14 in handle 8 when the jaws are closed by pressing the 60 handles together.

Having thus described my invention, what I claim is—

An alligator wrench comprising a casing, a fixed jaw and integral handle secured in said 65 casing, a jaw pivotally secured in the casing having gear-teeth formed integral therewith, a handle pivotally secured in the casing having gear-teeth formed integral therewith and engaging the teeth on the pivoted jaw, a coil-spring 70 engaging the handle of the fixed jaw and the pivoted handle to hold the handles normally in a separated position and the jaws open, a shield secured to the handle of the fixed jaw adjacent to the spring, and the 75 pivoted handle provided with a socket to receive the shield when the pivoted handle is actuated toward the handle of the fixed jaw, substantially as shown and described.

In witness whereof, I have hereunto set 80 my hand in presence of two subscribing witnesses.

SCOTT A. BROCKWAY.
